UNITED STATES PATENT OFFICE.

SAMUEL N. MILTON, OF SPENCER, IDAHO.

TOE-CALK FOR HORSESHOES.

1,101,139.

Specification of Letters Patent. Patented June 23, 1914.

Application filed May 6, 1913. Serial No. 765,948.

To all whom it may concern:

Be it known that I, SAMUEL N. MILTON, citizen of the United States, residing at Spencer, in the county of Fremont and State 5 of Idaho, have invented certain new and useful Improvements in Toe-Calks for Horseshoes, of which the following is a specification.

This invention relates to horse shoes and 10 more particularly to a novel toe-calk therefor, the same being provided with hardened inserts so arranged as to reinforce the calk for practically its entire width without, however, in themselves being of considerable 15 width.

For a full understanding of the invention reference is to be had to the following description and accompanying drawing, in which:

20 Figure 1 is a perspective view of the horse-shoe embodying the present invention. Fig. 2 is a vertical transverse sectional view on the line 2—2 of Fig. 1. Fig. 3 is a vertical section on the line 3—3 of Fig. 1. Fig. 25 4 is a similar view on the line 4—4 of Fig. 1. Fig. 5 is a perspective view illustrating the slightly modified form of the invention. Fig. 6 is a horizontal section on the line 6—6 of Fig. 5.

30 Corresponding and like parts are referred to in the following description and indicated in all the views of the accompanying drawing by the same reference characters.

The shoe embodying the present invention 35 consists essentially of a body 1 which is of the ordinary form and which at its sides is provided with the usual nail holes 2. At its toe the body 1 is provided with the usual toe-clip 3 and the heel-ends of 40 the body are turned downwardly substantially at right angles to the plane of the body to form heel-calks 4.

The toe-calk of the shoe is indicated in general by the reference numeral 5 and 45 will be presently more specifically described.

The inserts which are embedded in the heel ends of the shoe are in the nature of hardened steel blanks of a suitable thickness, width and length, and that one which is embedded 50 in the heel end through which the section 3—3 is taken is indicated specifically by the numeral 6 and as illustrated has its side disposed in planes with the said heel end of the body and with its particular heel-calk 4.

As clearly shown in Figs. 1 and 3 of the

drawings the insert 6 is for a portion of its length embedded in the heel-end of the body 1 and for the remainder of its length, and beyond a bend 7 formed therein, is embedded in the heel-calk 4. It will also be observed from inspection of said figures that the insert is disposed at its edges at the sides of the body and calk and that its lower end-edge is presented or exposed at the 65 lower end of the calk 4.

It will be observed that while of course the insert will in time wear down, rapid wearing away of the calk is prevented and the fact will further be appreciated that 70 the calk may wear down to the plane of the underside of the body 1 without liability of the insert becoming displaced.

The other heel-end of the body 1 has embedded in it an insert 8 which is in some 75 respects similar to the insert 6. The insert 8, however, is bent edge-wise and a portion is embedded in the body 1 and its remaining portion in the respective heel-calk 4.

As shown in Figs. 1 and 4 of the drawings 80 the insert 8 is exposed at its edges at the upper and under sides of the body 1 and front and rear sides of the calk. I have here illustrated the shoe as provided at one heel-end with the insert 6 and at the other heel-end with the insert 8, and while this arrangement is preferable, it is to be understood that I may employ two of the inserts 85 or two of the inserts 8 in a single shoe.

In the form of the invention shown in 90 Figs. 5 and 6 of the drawing, the insert indicated at 9 is approximately circular in cross-section and is arranged in the same manner as the inserts 6 and 8, previously described but exposed at the upper side of 95 the body 1 and the rear side of the calk 4, it being noted however, that more than one-half of the insert is embedded in the material of the body so as to provide against its displacement.

The toe-calk 5 above mentioned is in general shape and size similar to the toe-calk of the ordinary shoe. In its rear side, however, it is formed with grooves 10 and 11. These grooves are of dove-tail form and 105 the groove 10 extends vertically and is located approximately midway between the ends of the calk 5 whereas the grooves 11 are located one at each side of the groove 10 and are inclined upwardly toward each 110 other and away from the adjacent end-edges of the calk.

All of the grooves just mentioned extend from the lower edge of the calk to the plane of the under side of the body 1 and fitted and embedded in each of the grooves is an insert 12 of hardened steel, or the like. These inserts, are of course, of cross-sectional contour to completely fill the respective grooves and they constitute a firm reinforcement for the calk and provide against 10 its being rapidly worn away.

While the toe calk and its inserts is herein shown and described as integral with the toe of the shoe it will of course be understood that it may be formed separate therefrom and welded or otherwise secured thereto by the blacksmith.

Having thus described the invention what is claimed as new is:—

1. A horse shoe provided with a toe calk projecting downwardly from its under side and provided with relatively angularly disposed grooves extending from the lower ends of the calk to the upper ends thereof, the side walls of the grooves being under-cut,

and beveled edged inserts fitted in the 25 grooves and terminating at their lower ends at the lower end of the calk and at their upper ends resting against the under side of the shoe.

2. A horse shoe having a toe calk projecting 30 downwardly from its under side and relatively wide, the calk being formed in its rear side and about its middle with a substantially vertically extending groove and being formed with other grooves located at 35 the sides of the first mentioned groove, the last mentioned grooves being inclined downwardly and outwardly from the first mentioned groove at the respective sides of the latter and having their lower terminals near 40 the corners of the calk, and inserts arranged within the grooves.

In testimony whereof I affix my signature in presence of two witnesses.

SAMUEL N. MILTON. [L.S.]
